DESIGN FOR A GAME BOARD

Ralph A. Bradley, Kansas City, Mo., assignor of one-third to Carl W. Jackson, Minneapolis, Minn., and one-third to Louis Brown,
Kansas City, Mo.

Application January 24, 1940, Serial No. 89,680

Term of patent 7 years

To all whom it may concern:

Be it known that I, Ralph A. Bradley, a citizen of the United States, residing at Kansas City, in the county of Jackson and State of Missouri, have invented a new, original, and ornamental Design for a Game Board, of which the following is a specification, reference being had to the accompanying drawing, forming a part thereof.

The figure is a plan view of the game board, showing my new design.

The game board is of no appreciable thickness and none of the features of the design project from the surface.

I claim:

The ornamental design for a game board, as shown and described.

RALPH A. BRADLEY.
